(57) **CLAIM**

The ornamental design for a register gear adapter plate, as shown and described.

DESCRIPTION

The file for this patent or application contains a least one drawing executed in color. Copies of this patent or patent application publication with color drawing(s) will be provided by the Office upon request and payment of the necessary fee.

FIG. 1 is a front perspective view of a register gear adapter plate in a yellow color, showing my new design;

FIG. 2 is a back perspective view thereof;

FIG. 3 is a front view thereof;

FIG. 4 is a rear view thereof;

FIG. 5 is a top view thereof;

FIG. 6 is a bottom view thereof;

FIG. 7 is a right view thereof;

FIG. 8 is a left view thereof;

FIG. 9 is a front perspective view of a black and white line drawing variant of the register gear adapter plate of FIG. 1;

FIG. 10 is a back perspective view thereof;

FIG. 11 is a front view thereof;

FIG. 12 is a rear view thereof;

FIG. 13 is a top view thereof;

FIG. 14 is a bottom view thereof;

FIG. 15 is a right view thereof; and,

FIG. 16 is a left view thereof.

The broken line showing on the drawing disclosure depicts unclaimed portions of the register gear adapter plate which form no part of the claimed design.
